PAUL S. BEAR, OF ELKHART, INDIANA, ASSIGNOR, BY MESNE ASSIGNMENTS, TO MINNEAPOLIS-HONEYWELL REGULATOR COMPANY, OF MINNEAPOLIS, MINNESOTA, A CORPORATION OF DELAWARE

MERCURY SWITCH

Application filed June 18, 1930. Serial No. 461,922.

This invention relates to improvements in switches and more particularly to those of the type known in the art as mercury switches.

Switches of this type comprise a hermetically sealed envelope of soft glass, electrodes sealed therein and a body of mercury movable in the envelope so that in one position of the latter the circuit through the electrodes is completed, whereas when tilted or otherwise moved into a position in which the mercury may flow out of engagement with the electrodes, the circuit is broken. Generally speaking, there are two types of these switches now in general use, one employing an envelope of soft glass, such as the lead or lime varieties with the electrodes suspended therein and in such position that they are bridged by the body of mercury when the tube is moved into a certain position. In this type of mercury switch, the arcing, both at the make and the break of the circuit, has a pronounced deteriorating effect upon the electrodes. As is well known, this action on the electrodes affecting them to such an extent that the life of the switch is materially shortened. Further, soft glass is not adapted to withstand the playing of an arc thereon. In the other type of switch referred to, the envelope is made of quartz or hard glass, such as Pyrex or the like, which, as is well known, is substantially unaffected by the heat of the arc. In this type of switch, therefore, owing to the hard glass envelope, the electrodes and mercury may be so arranged that a mercury make and break directly on the surface of the envelope may be utilized, the electrodes in these switches being usually arranged in wells or the like, formed in the envelope, or so positioned relative to one another that each of them is at all times immersed in mercury so that all of the arcing which occurs, occurs directly between mercury and mercury as the tube is tilted or otherwise moved to make and break the circuit. As is well known, a mercury to mercury make and break is desirable for a number of reasons. Chief among these is the fact that in such a switch, the electrodes are not subjected to deteriorating influences of any kind.

Then too, the arcing is less in a mercury to mercury make and break, as is well known. Furthermore, any arcing which does occur in a switch of this type merely results in a vaporization of a minute portion of the mercury at the point of contact which immediately condenses upon quenching of the arc and flows back into the main body again. Despite the many advantages incident to the utilization of a mercury to mercury contact in switches of this character, they have not come into general use, principally because of the cost of the hard glass and the difficulties encountered in hermetically sealing the leading-in wires or electrodes into an envelope made of such glass.

Various types of mercury switches have been designed to overcome the above disadvantages and chief among these is the type employing an inner sleeve of quartz or Pyrex glass which is cemented to the inner surface of the glass envelope. Such a design, however, necessitates a hand-sealed switch which materially adds to the cost thereof. In addition to this, another and more serious disadvantage results from the use of cement to hold the inner sleeve in place. After the switch has made a large number of contacts in the field, the mercury begins to leak through the cemented portion and thus causes a connection between the body of mercury in the sleeve and the body of mercury which lies outside the sleeve. Such a condition, of course, destroys the effective operation of the switch and it is no longer useful.

An object, therefore, of my invention is to provide a mercury switch of the inner-sleeve type which may be machine-sealed, thus materially reducing the cost thereof.

Another object is to eliminate the necessity of using expensive glass, such as quartz, Pyrex, or the like.

A further object is the provision of improved means in the way of construction and arrangement of the parts, all tending towards a more practical and commercial development and a more satisfactory solution of the various problems encountered heretofore.

Other objects will appear from the follow-

ing specifications taken in connection with the accompanying drawing wherein:

Fig. 1 is a longitudinal sectional view of a mercury switch constructed in accordance with the present invention, and showing the switch in open or circuit breaking position.

Fig. 2 is a similar view showing the switch tilted to the closed or circuit making position.

Fig. 3 is view in section taken on line 3—3 of Fig. 1, the mercury being omitted for the sake of clearness in illustration.

Fig. 4 is a detail view in end elevation of the ceramic ring.

Fig. 5 is a fragmentary view partly in side elevation and partly in section, showing a modified construction of the ceramic ring.

Referring more in detail to the drawing, the switch comprises an outer sealed envelope 1 which, as already stated, is preferably, for commercial and economic reasons, made of glass of the softer varieties. This envelope is substantially capsule shaped, through which leading-in wires 2 and 3 extend into the interior. These leading-in wires may be of the usual copper clad type and are hermetically sealed in the wall of the envelope as at 4 at their points of projection therethrough. Electrodes 5 and 6, preferably formed of some wire which is not affected by the mercury, such, for instance, as iron, nickel, tungsten or the like, are welded as at 7, to the leading-in wires 2 and 3 immediately inwardly of the seals 4. The movable body of mercury in the envelope bears reference character 12 and, as will be observed, in one position, or in other words, the position shown in Fig. 2 of the drawing, this mercury completes the circuit between the electrodes, whereas, as will be observed, upon tilting or oscillation of the envelope into an opposite or reverse position, the mercury will flow to the other end of the envelope, thus interrupting the circuit. The envelope of these switches is generally filled with an inert gas, such as hydrogen, in order to retard chemical action and to assist in suppressing the arcing which results in prolonging the life of the switch.

The switch as thus far described is much the same as switches heretofore developed and which are at the present time in rather general use, and in which the make and break occurs directly between the electrodes and mercury, resulting in the deteriorating effects above pointed out. To overcome the disadvantages inherent in this type of switch heretofore constructed and to, in reality, transform the same into a mercury to mercury make and break type switch, it is proposed, according to the present invention, to provide means for constantly maintaining a portion of the mercury around each electrode.

In carrying out the present invention, a tubular piece of glass 9, which may also be

of the soft variety, is first cemented to a circular piece of ceramic or other arc resisting material 10, such as high heat resisting porcelain, Alundum, or the like. This ring-like piece 10, is provided with a shallow annular slot 11, adapted to fit the end of the inner glass tube 9. As before stated, the glass tube 9, is cemented to the ring 10 by means of dipping one end of the tubing in a suitable cement and then pressing it into the annular slot 11 provided in the ring 10. This assembly is then placed in an oven and baked until the cement is properly set. Following this operation, the inner tubing 9 with the ring 10 attached thereto and the leading-in wire and electrode assembly 2 and 5 is placed in a chuck with the envelope 1. The formation and relative position of envelope 1 and inner tube 9 at this time is indicated by dotted line in Fig. 3. The whole assembly is then heated until the glass is brought to a melting point, at which time a sealing head, of the usual construction, is clamped against the assembly on either side, thus making a hermetically tight seal and fusing the tubing 9 with the envelope 1 in a pinch seal formation as shown in full lines in Fig. 3.

The usual tubulation (not shown) is formed in the conventional manner and the leading-in wire and the electrode assembly 3 and 6 is pinch-sealed into the opposite end of the envelope 1, also in the usual manner. The switch is then filled with the proper amount of mercury, evacuated and filled with hydrogen or other inert arc-suppressing gas through the tubulation, and the envelope sealed off as indicated by the reference character 13.

It will be noted that leading-in wires 2 and 3 are sealed into the envelope in a slantwise position, and that consequently the electrodes 5 and 6 are similarly disposed, the electrode 5 terminating very near the floor 14 of the tubing 9 well past the center thereof, and the electrode 6 terminating close to the floor of the envelope 1. This is done so that the electrodes 5 and 6 will at all times be submerged in the mercury, whether the switch be in open or closed position.

A body of mercury 12 substantially in the amount shown is placed in the envelope 1. This mercury being partly in the inner sleeve 9, and to right of the ring 10, and partly in the envelope proper, such parts being united into a single continuous body when the tube is tilted to circuit making position, substantially as shown in Fig. 2. As will be observed, the body of mercury after separation thereof into two portions, one on one side and one on the other side of the ring 10, reunites in a single body again upon tilting of the tube, as shown, and in thus reuniting, the portion to the right of the ring 10 in Fig. 2 flows along the floor of the tubing 9 and over the ring 10, meeting the other portion of

mercury which simultaneously flows along the floor of the envelope 1 toward the ring 10, the quantity of mercury and the general construction and arrangement of parts being such as to definitely bring about this making and breaking between these two portions of mercury within the ceramic ring 10. Thus, any arcing which may occur at the make and break occurs at this point which, as will be observed, is located substantially at the longitudinal axis of the envelope and at a substantial distance from both ends thereof. Thus, the envelope is protected against all the deteriorating influences of the arc.

Referring now to Fig. 5, in which is shown a somewhat different construction of the ceramic ring 10, the ring 10 is made with an extended annular flange 16 slightly less in circumference than that of the ring proper, the reduction in circumference of the flanged portion 16 being enough to allow the tube 9 to slip loosely over said flanged portion 16 of the ring 10. In assembling the tube 9 with the flanged ring, a cementitious substance 15, capable of expanding slightly upon being heated, is first applied to the circumferential surface of the flanged portion 16. The tube 9 is then slipped over the flange until the end rests snugly against the shoulder of the ring portion 10. At this time, the assembly is placed in an oven, as before, and baked until the cement has properly expanded and set. An expanding cementitious substance is used in order to make a very tight fit between the tube 9 and the ring 10 and flange 16.

The cement mentioned herein may consist of a pasty mixture of asbestos, sodium silicate and water. This cement forms a tight joint between the glass and the refractory ring 10. It is desirable that such cement have a coefficient of expansion approximately the same as that of the material composing the inner sleeve, as otherwise the alternate heating and cooling of the ring 10 may cause the inner sleeve or the refractory ring to crack by reason of the strain produced by the unequal expansion of the sleeve and ring. A suitable compound for a cement is:

Sodium silicate	2246.7 cc.
Water	394.1 cc.
Ground asbestos	857.9 grams

The above formula will make approximately ten pounds of cement

The nearer the coefficient of expansion of the glass is to that of the refractory ring, the more asbestos is to be used in the above formula. Magnesium silicate, $MgSiO_3$, magnesium oxide, MgO , may replace the asbestos. The sodium silicate may also be diluted with some water before use. Another cement that has proven satisfactory is made up of lead phosphate, $Ph_3(PO_4)_2$, and sodium silicate.

This is especially desirable when the glass employed has a high coefficient of expansion.

It will be seen that by my invention, soft glass may be used throughout the mercury switch, and hand labor, to a great extent, is eliminated, thus materially reducing the cost thereof and at the same time making a mercury switch which is superior to those now manufactured.

It will be appreciated that the invention in its entirety may, of course, take various forms and modifications in addition to the specific example herein illustrated and described, but it is desired that the appended claims be interpreted broadly and of a scope commensurate with the spirit of the invention and not limited or restricted in any manner to the particular embodiments of the invention shown.

I claim:

1. A mercury switch comprising an outer envelope, an inner protective sleeve, said envelope and said sleeve being constituted of glass having substantially the same coefficient of expansion, electrodes extending into said sleeve and into the space the outer envelope exterior of the sleeve, a pinch seal uniting one end of the sleeve and one end of the envelope and forming a seal about one at least, of said electrodes and a body of mercury co-operable with the electrodes and uniting and dividing on a surface of said sleeve.

2. A mercury switch comprising an outer envelope, an inner protective sleeve, a pinch seal uniting one end of the sleeve to one end of the envelope and a body of mercury within the envelope and uniting and dividing on the inner surface of said sleeve.

3. A mercury switch comprising an outer soft glass envelope, an inner soft glass protective sleeve, an electrode projecting into the protective sleeve, a pinch seal uniting one end of the sleeve and one end of the envelope, and forming a seal about said electrode, a co-operable electrode sealed through the outer envelope and a body of mercury co-operable with the electrodes and uniting and dividing on a surface of the inner sleeve.

4. A mercury switch comprising an outer soft glass envelope, an inner soft glass protective sleeve, an arc resistant collar supported by said sleeve, an electrode projecting into the protective sleeve, a pinch seal uniting one end of the sleeve and one end of the envelope and forming a seal about said electrode, a co-operable electrode sealed through the outer envelope and a body of mercury co-operable with the electrodes and uniting and dividing on a surface of the collar.

In testimony whereof he affixes his signature.

PAUL S. BEAR.
